ADJUSTABLE EQUALIZER FULCRUM
ARRANGEMENT

Edward J. Harley, Philadelphia, Pa.

Application April 22, 1938, Serial No. 203,591

8 Claims. (Cl. 105—82)

This invention relates generally to spring rigging equalizing systems for locomotives and particularly to an improved adjustable fulcrum for equalizing beams applicable to two or four wheel leading or trailing locomotive trucks or other parts of the main equalizing spring rigging system.

A great many arrangements have heretofore been suggested or used to provide an adjustable fulcrum between an equalizing beam and the locomotive or truck frames in order to properly distribute the load on the truck or locomotive wheels. One customary arrangement employs several longitudinal spaced sets of holes, the fulcrum pin being inserted in the sets of holes which produce, or comes the nearest to producing, the desired weight distribution. The number of possible adjustments in such an arrangement is limited to the few number of holes usually three. Inasmuch as only one hole would be ultimately used, it is seen that unnecessary cost is involved in initially providing the extra holes as well as providing only a limited number of possible adjustments. Many other prior arrangements have employed fulcrum blocks with a plurality of holes or a single hole is eccentrically located in a multi-hole block that is bodily removable and insertable in different angular positions. These arrangements have the same above objection of providing a very limited number of possible adjustments. Another objection to these prior arrangements is that the adjustment from one position to another cannot be made with maximum ease and dispatch.

It is an object of my invention to provide an improved equalizing beam fulcrum arrangement that is adjustable for an infinite number of positions thereby permitting a very effective and highly satisfactory distribution of weight.

A further object is to provide an improved adjustable equalizing beam fulcrum that can be conveniently and effectively adjusted with minimum time and effort as well as minimum initial cost.

Another object is to provide an improved adjustable fulcrum for equalizing beams that is relatively simple and compact and yet has a high degree of sturdiness and durability.

Other objects and advantages will be more apparent to those skilled in the art from the following description of the accompanying drawings in which:

Fig. 1 is a fragmentary side elevation of a locomotive embodying my improved adjustable beam fulcrum in connection with a trailing truck;

Fig. 2 is an enlarged side elevation of the fulcrum construction and truck frame adjacent thereto;

Fig. 2a is a fragmentary perspective of an equalizing beam used in Fig. 2;

Fig. 3 is a vertical section taken on the line 3—3 of Fig. 2;

Fig. 4 is an enlarged side elevation of a modified form of adjustable fulcrum together with a portion of the truck or locomotive frame adjacent thereto;

Fig. 5 is a transverse section taken on the line 5—5 of Fig. 4;

Fig. 6 is a horizontal section taken on the line 6—6 of Fig. 4;

Fig. 7 is a perspective of one portion of an equalizing beam with the fulcrum seat shown thereon;

Fig. 8 is a perspective of a combined fulcrum block and pin.

In the particular embodiments of the invention, such as are disclosed herein merely for the purpose of illustrating certain specific forms among possible others that the invention might take in practice, I have shown a conventional spring rigging system having main locomotive driving springs 1 and truck springs 2 of a four wheel trailing truck. The springs are connected to the truck frame 3 and main locomotive frame 4 through usual equalizing beams, all of which are generally numbered 5 and the springs in turn are supported on truck wheels 6 and driving wheels 7. For the purpose of illustrating my improved fulcrum only the truck frame need be described although various other types of frames could be obviously used. The term frame as herein used in reference to a locomotive refers to either a locomotive or truck frame.

Each side of the frame has a pair of longitudinally extending pieces 8 and 9 provided with longitudinal openings 10 and 11 in transverse alignment with each other. The frame is supported on the equalizing beams through a usual fulcrum pin 12 the opposite ends of which are journaled in fulcrum blocks 13 and 14 identical to each other and bodily shiftable in a longitudinal rectilinear position. Each block has a substantially rectangular portion with upper and lower parallel surfaces 15 fitting within their respective longitudinal frame openings 10 and 11 and snugly slidably engaging the walls thereof. The rectangular portions of these blocks terminate flush with the inner vertical surfaces of the frame sides 8 and 9 and project laterally beyond the 55

outer surfaces thereof. An extension 16 projects downwardly from the lateral portion of the blocks for overlapping and engaging the outer surfaces 17 of the frame 8 and 9. The equalizing beam 5 has an elongated horizontal slot 18 snugly receiving a longitudinally slidable rectangular fulcrum block 19. All of the fulcrum blocks have a single cylindrical opening for fulcrum pin 12.

10 In operation, the equalizing system of the locomotive is completely assembled with the shiftable blocks 13, 14 and 19 approximately longitudinally positioned in their respective elongated openings. These blocks may if desired be temporarily tacked in place by welding between the blocks and frame at corners such as 20 and 21 of the frame blocks and at the corners of the equalizing beam and beam blocks 19 as indicated at 22. After the locomotive is completely assembled and weighed, 15 if it is then necessary to shift the fulcrum pin of any of the equalizing beams to adjust the distribution of load on the wheels, the temporary tacking can be easily cut away to allow the shiftable blocks to be moved in either direction and 20 to any desired extent lengthwise of the slots 10, 11 and 18. When the proper positions of the fulcrums are obtained, the fulcrum blocks 13, 14 and 19 are then suitably permanently secured in 25 position preferably by completely welding at the various points of juncture previously indicated for temporary tacking. Even this permanent welding can be readily removed at any future time in the event that subsequent operation of, or 30 alterations or additions to, the locomotive should require further shifting of any fulcrum. In any case, however, it is seen that the position of the fulcrum can be determined and obtained not only with maximum ease and minimum expense but also with great accuracy. It is never necessary to bodily remove or replace any of the pins or blocks to effect an adjustment all of the parts simply remaining in their normal operative relation regardless of the infinite number of adjustable positions that are available. Such an 35 arrangement is conducive to maximum flexibility of production and complete satisfaction to a railroad as to the weight distribution desired by it. It will also be apparent that instead of using temporary tacking, the fulcrum blocks may be placed in position and left untacked, there being sufficient supporting contact between the various parts. In this case, after the locomotive is weighed the fulcrum blocks may be shifted as 40 necessary and then permanently secured to the locomotive or truck frames and to the equalizing beams as previously mentioned.

From the foregoing disclosure it is seen that my improved arrangement allows an infinite 45 number of positional adjustments of the fulcrums with a structure of great simplicity and sturdiness, it being noted that the longitudinal bodily shifting of the fulcrum blocks permits the elongated openings to have a minimum vertical 50 height and therefore it is only necessary to remove a minimum amount of material from the equalizing beam or from the frame and consequently maximum strength is maintained without sacrificing the incremental adjustments 55 while at the same time permitting the very maximum range of adjustment to be made.

In the modification of Figs. 4 to 8, the frame is provided with transversely aligned elongated openings 25 located substantially above the level 60 of the upper edge of an equalizing beam 26. A

fulcrum seat block 27 is placed on the upper edge of the equalizing beam while a combined fulcrum pin and block generally indicated at 28 is associated with the frame. As shown in Figs. 4, 5 and 8, this combined block comprises inner and outer vertical portions 29 and 30 connected by a transverse upper portion 31 and a semi-cylindrical element 32 which is herein referred to as a fulcrum pin. Projecting downwardly from the outer portion 30 is an extension 33 corresponding to the extension 16 of the preferred form. This combined block is inserted within the openings 25 formed in each of the frame walls 35 and 36 with the upper and lower horizontal surfaces of the vertical portions 29 and 30 snugly and longitudinally slidably fitting the parallel walls of openings 25 while the extension 33 rests against the outer surface of the frame side 35, Fig. 5. The fulcrum pin 32 is seated in block 27 to support the weight of the locomotive on the equalizing beam. To prevent the semi-cylindrical pin and seat from completely separating at any time, a stud 38 is fastened in the frame beneath the equalizing beam.

In this modification, the equalizing system is assembled and the shiftable fulcrum blocks temporarily tacked in their approximate position or loosely left therein, but in either case after the locomotive is weighed the blocks 27 and 28 may be longitudinally shifted to adjust the position of a fulcrum. The block 27 is secured to the equalizing beam 26 as by welding at 39 while the frame block 28 is welded to the frame as at 40. This arrangement has all the advantages of the preferred form. If a very small adjustment is necessary in either form, the blocks associated with the equalizing beams may be shifted thereon without disturbing the frame blocks but for most 45 adjustments it is desirable to shift both sets of blocks to maintain the normal vertical position of the spring hanger links.

It will of course be understood that various changes in details of construction and arrangement of parts be made by those skilled in the art without departing from the spirit of the invention as set forth in the appended claims.

I claim:

1. The combination in a locomotive comprising, a frame having transversely opposed spaced walls with longitudinally elongated but transversely aligned openings therein, a spring rigging system having an equalizing beam disposed between said spaced walls, a fulcrum pin for supporting said frame on said beam, pin supporting means disposed within said openings and being longitudinally incrementally bodily shiftable therein in a rectilinear direction for adjusting the position of the fulcrum pin relative to said frame, and means for permanently and immovably securing said pin supporting means in any incremental position to which it is bodily longitudinally adjusted.

2. The combination in a locomotive comprising, a frame having opposed spaced walls with longitudinally extending but transversely aligned openings therein, a spring rigging system having an equalizing beam disposed between said walls, a fulcrum pin, fulcrum blocks associated with said equalizing beam and frame walls for connecting the beam and frame together by said pin, said fulcrum blocks being incrementally bodily shiftable in a longitudinal rectilinear direction in said openings relative to said beam and frame to adjust the position of the fulcrum

pin, and means for securing said blocks in their incrementally adjusted position.

3. The combination in a locomotive comprising, a frame having opposed spaced walls, a 5 spring rigging system having an equalizing beam disposed between said walls, said opposed walls having longitudinal openings in transverse alignment with each other, fulcrum block means disposed in each of said aligned openings so as to be incrementally longitudinally bodily shiftable thereof in a rectilinear direction within said 10 openings, a fulcrum pin associated with said block means, and longitudinally adjustable means associated with said beam for supporting the intermediate portion of said pin by said beam.

4. The combination in a locomotive comprising, a frame having opposed spaced walls, a 15 spring rigging system including an equalizing beam disposed between said walls, said frame and beam having transversely aligned longitudinally elongated openings, fulcrum blocks disposed respectively in said openings so as to be longitudinally bodily shiftable therein in a rectilinear direction, a fulcrum pin journalled in said blocks, 20 and means for holding said blocks in position within said openings.

5. The combination in a locomotive comprising, a frame and a spring rigging system having an equalizing beam, said frame having opposed 25 vertical sides between which said equalizing beam is disposed, said frame sides and beam having transversely aligned longitudinally elongated openings, fulcrum blocks disposed within the openings of said frame sides and having an 30 extension overlapping the frame sides, a fulcrum block disposed within the opening in said equalizing beam, a fulcrum pin journalled in all of said blocks, said openings being arranged to allow said blocks to be bodily longitudinally 35 shifted therein in a rectilinear direction to effect any desired extent of adjustment of the fulcrum pin, and means for securing said blocks to their respective frame and beam elements.

6. The combination set forth in claim 5 further characterized in that said securing means 40 engages said fulcrum block extensions and frame.

7. The combination in a locomotive comprising-

ing, a frame and a spring rigging system having an equalizing beam, said frame having opposed vertical sides between which said equalizing beam is disposed, said frame sides and beam having transversely aligned longitudinally elongated openings, fulcrum blocks disposed within the openings of said frame sides and having an extension overlapping the frame sides, a fulcrum block disposed within the opening in said equalizing beam, a fulcrum pin journalled in all 10 of said blocks, said openings being arranged to allow said blocks to be bodily longitudinally shifted therein to effect any desired extent of adjustment of the fulcrum pin, means for securing said blocks to their respective frame and 15 beam elements, said securing means including a welded seam between said fulcrum block extensions and frame sides, and welded seams between 20 said equalizing beam and its fulcrum block.

8. The combination in a locomotive comprising, a frame and a spring rigging system having an equalizing beam, said frame having opposed vertical sides between which said equalizing beam is disposed, said frame sides and beam having transversely aligned longitudinally elongated openings, fulcrum blocks disposed within the openings of said frame sides and having an extension overlapping the frame sides, a fulcrum block disposed within the opening in said 30 equalizing beam, a fulcrum pin journalled in all of said blocks, said openings being arranged to allow said blocks to be bodily longitudinally shifted therein to effect any desired extent of 35 adjustment of the fulcrum pin, and means for securing said blocks to their respective frame and beam elements, said securing means including welded seams between said frame and equalizing beam and their respective fulcrum blocks thereby allowing said blocks to be secured 40 in any position to which they are incrementally adjusted, said openings providing lateral access to said seams whereby said beams and frame may be permanently connected together after 45 completion of the assembly and weight distribution of the locomotive.

EDWARD J. HARLEY.
